UNITED STATES PATENT OFFICE.

WALTHER FRÖB, OF EBERSWALDE, NEAR BERLIN, GERMANY, ASSIGNOR TO THE FIRM
FRANZ SEIFFERT & CO., AKTIENGESELLSCHAFT, OF BERLIN, GERMANY.

SLIDE STOP VALVE.

Application filed October 11, 1926, Serial No. 140,952, and in Germany October 16, 1925.

- In slide stop valves of the types hitherto known, which are provided with a packing on each side and in which the tightening surfaces of the slide face and of the casing are not in contact with each other during the up-and down-movement, the contact is brought about and discontinued by the axial spreading of the two-part slide face when in its lower position.
- 5 The slide valve according to the present invention is distinguished from the types mentioned above by its non-spreadable slide face, while both the tightening surfaces of the casing are axially movable. This improved 55 slide is intended for use especially in connection with high-pressure steam or another fluid under high pressure, and its chief characteristic features reside in that frictional contact on both sides of the sliding member 60 proper with the opposite tightening faces of certain tubular slidable members hereinafter fully dealt with is completely prevented, in that two of said tubular slidable members are provided and these members can be 65 moved towards and pressed against, as well as withdrawn from, the said slide proper, this latter being movable only after certain gaps have been formed between it and the 70 said slidable tubular members, all as fully described hereinafter.
- An embodiment of the slide stop valve according to the present invention is shown in the accompanying drawings wherein:
- 75 Figs. I-IV are vertical longitudinal sections, Fig. I showing the slide valve closed, Figs. II and III each showing it in one of the intermediate positions, and Fig. IV showing the valve fully opened;
- 80 Fig. V is a cross-section on line V—V of Fig. I, and
- 85 Fig. VI is a cross-section on line VI—VI of Fig. I.
- In all of the figures, 1 is the valve casing, 2 is a hollow stem which is movable up and 90 down and can be rotated by means of a hand-wheel 4 and an intermediate bush or sleeve 3. At the top the stem 2 is provided with a collar 5 and at the bottom it has exterior screw threads of low pitch 6 and interior 95 screw threads following the same direction but having a higher pitch, in the present case four times that of the exterior thread. In 100 the upper part 8 of the casing there is a fixed stop 7 against which a collar 5 will abut, thereby limiting the downward movement of the hollow stem 2. There is also a movable stop 9 in the upper part of the casing which is pushed by the cooperation of the hand-wheel 4, the bush 3, and bevel-gear 10.
- 105 11 is a nut having pins 12 (Fig. V) at diametrically opposed places which serve as bearings for a frame 13. The latter has two pairs of arms 14 which embrace guiding ribs 15 provided within the casing 1 whereby 110 both the frame 13 and the nut 11 are prevented from rotating. The ribs 15 are situated in the same plane with the axis of the stem 2 and admit of a balancing movement of the frame about the pins 12.
- 115 At right angles to the pins 12 two pins 16 are provided on the frame 13 on which two two-armed levers 17 are mounted, to the ends of which rods 18 are linked. Each of these four rods actuates one of four bell-crank levers 19 which are mounted within the lower part of the casing 1. Each two of these bell-crank levers 19 actuate one of two tubes 20 slidably mounted in the casing. The arrangement of parts 11-17 forms a 120 Cardan suspension for the rods 18 which are thereby enabled uniformly to actuate the bell-crank levers 19 whose driving arms are moving in grooves 21 provided in the sliding tubes 20.
- 125 The end faces 22 of the sliding tubes 20 form the tightening surfaces of the casing. Packing rings or the like 23 serve to tighten the sliding tubes 20 and the casing 1 relatively to one another.
- 130 The sliding plate 24 is carried by a non-rotatable threaded stem 26 engaging the interior threading of the hollow stem 2. The plate 24 is provided with lateral lugs 27, by means of which it is guided on ribs 28 in the casing 1 which are running parallel to the stem 26. The downward movement of the plate 24 is limited by a stop 29.
- 135 Two bars 30 running in guideways provided in the casing are taken along by the 140 sliding tubes 20 by means of pins 31, the latter penetrating through axial slots 32 in that part of the casing surrounding the tubes 20. The ends 33 of the bars 30 which are

adjacent the sliding plate 24 project beyond the tightening surfaces 22 of the sliding tubes 20.

The operation of the slide valve is as follows: In closed condition the plate 24 is in its lowermost position, the sliding tubes 20 being firmly pressed against it. The bars 30 overlap the plate 24, and the hollow stem 2 is in its raised position. When the hand-wheel 4 is turned in the direction of the arrow, i. e. in a counter-clockwise direction, each rotation will cause the hollow stem 2 to screw itself down four threads, the bars 30 holding the sliding plate 24 in fixed position. The nut 11 will rise on the stem 2 one thread per revolution, thus being actually lowered three threads. By means of the Cardan suspension 11-17 this motion is transmitted to the rods 18, whereby the bell-crank levers 19 are caused to push the sliding tubes 20 outwardly until the bars 30 will release the plate 24, as clearly appears from Fig. II.

Upon the plate 24 being released by the bars 30 the sliding tubes 20, and with them the nut 11, will be arrested; the hollow stem 2 will screw itself down into the nut one thread per revolution while the stem 26 will screw itself into the stem 2 four threads per revolution. The plate 24 will also rise three threads per revolution until the collar 5 abuts against the stop 7, the movable stop 9 also having been pushed close up to the collar 5, as is shown in Fig. III. In this position the slide valve is opened far enough for action.

On further rotation of the hand-wheel 4 the hollow stem 2 will stop. While the plate 24 will now rise four threads per revolution the nut 11 rises one thread per revolution and will, by means of the Cardan suspension 11-17, the rods 18, and the bell-crank levers 19, draw the sliding tubes 20 together until the tightening surfaces 22 come in contact. Simultaneously the movable stop 9 will move forward far enough to overlap the collar 5 as shown in Fig. IV. In this position the interior of the valve casing is shut off from steam or the like and protected against dirtying.

Rotation of the hand-wheel 4 in opposite direction, i. e. in clockwise direction, will cause the stem 26 and plate 24 to move downward. Simultaneously the nut 11 will also move downward, thereby pulling the tubes 20 apart until the movable stop 9 will release the collar 5 (see Fig. III). Now the sliding tubes 20 and the nut 11 will stop, the hollow stem 2 will rise one thread per revolution, while the plate 24 will descend three threads per revolution. As soon as the plate 24 is supported on the stop 29 (Fig. II) the hollow stem 2 will screw itself up four threads per revolution, carrying the nut 11 up three threads per revolution whereby the sliding

tubes 20 will be drawn towards the plate 24, as shown in Fig. I.

What I claim as new and desire to secure by Letters Patent is:—

1. A slide stop-valve, comprising in combination, a casing and two oppositely located branches extending thereinto; a shiftable tubular member in each of said branches; a slide adapted to be introduced between, and withdrawn from, said tubular members; an operating mechanism for said slide and the tubular members and comprising means for lowering and lifting the slide, means for pressing the tightening faces of the tubular members against, and for withdrawing them from, the lowered slide, and means for pressing the tubular end members against one another when the slide is lifted. 75

2. A slide stop-valve, comprising in combination, a casing and two oppositely located branches extending thereinto; a shiftable tubular member in each of said branches; a slide adapted to be introduced between, and withdrawn from, said tubular members; an operating mechanism for said slide and the tubular members and comprising means for lowering and lifting the slide, means for pressing the tightening faces of the tubular members against, and for withdrawing them from, the lowered slide, and means for pressing the tubular end members against one another when the slide is lifted; and members coupling said several means in such a manner that the said tubular members are shiftable towards and away from the said slide when the slide is in its closing position. 95

3. A slide stop-valve, comprising in combination, a casing and two oppositely located branches extending thereinto; a shiftable tubular member in each of said branches; a slide adapted to be introduced between, and withdrawn from, said tubular members; an operating mechanism for said slide and the tubular members and comprising means for lowering and lifting the slide, means for pressing the tightening faces of the tubular members against, and for withdrawing them from, the lowered slide, and means for pressing the tubular end members against one another when the slide is lifted; and members coupling said several means with each other in such a manner that the tubular members are moved towards, and pressed against, each other after the slide is lifted. 105

4. A slide stop-valve, comprising in combination, a casing and two oppositely located branches extending thereinto; a shiftable tubular member in each of said branches; a slide adapted to be introduced between, and withdrawn from, said tubular members; a non-rotary threaded spindle extending upwardly from said slide, a rotary hollow spindle having an interior thread engaged by the thread of said non-rotary spindle, said hollow spindle further having an ex- 120
125
130

- terior thread and being axially movable, means for turning, as well as lifting and lowering, said hollow spindle, a collar upon the same, a stationary abutment member and
- 5 a movable abutment member both co-operating with said collar, a nut upon the exterior thread of the hollow spindle, rods extending downwardly from said nut to the shiftable tubular members and being indirectly
- 10 and movably connected with the said nut, bell-crank levers carried by the said branches of the casing and being connected at one arm with one of said rods and at the other arm with one of the said shiftable tubular
- 15 members, substantially as set forth.
5. A slide stop-valve, comprising in combination, a casing and two oppositely located branches extending thereto; a shiftable tubular member in each of said branches; a slide adapted to be introduced between, and withdrawn from, said tubular members; a non-rotary threaded spindle extending upwardly from said slide, a rotary hollow spindle having an interior thread engaged by the thread of said non-rotary spindle, said hollow spindle further having an exterior thread and being axially movable, means for turning, as well as lifting and lowering, said hollow spindle, a collar upon the hollow spindle, a stationary abutment member and a movable abutment mem-
- 20 ber both co-operating with said collar, a nut upon the exterior thread of the hollow spindle, pivots projecting from said nut on opposite sides of the same, a horizontal frame carried by said pivots, other pivots extending from said frame at right angles with respect to the first-mentioned pivots, double-armed levers carried by said other pivots, rods extending downwardly from said levers to the shiftable tubular members
- 25 and being indirectly and movably connected with the said nut, bell-crank levers carried by the said branches of the casing and being connected at one arm with one of said rods and at the other arm with one of the said
- 30 members, substantially as set forth.
- 35 nut upon the exterior thread of the hollow spindle, rods extending downwardly from said nut to the shiftable tubular members and being indirectly and movably connected with the said nut, bell-crank levers carried
- 40 by the said branches of the casing and being
- connected at one arm with one of said rods and at the other arm with one of the said shiftable tubular members, substantially as set forth.
6. A slide stop-valve, comprising in combination, a casing and two oppositely located branches extending thereto; a shiftable tubular member in each of said branches; a slide adapted to be introduced between, and withdrawn from, said tubular members; a non-rotary threaded spindle extending upwardly from said slide, a rotary hollow spindle having an interior thread engaged by the thread of said non-rotary spindle, said hollow spindle further having an exterior thread and being axially movable, means for turning, as well as lifting and lowering, said hollow spindle, a collar upon the hollow spindle, a stationary abutment member and a movable abutment mem-
- 45 ber both co-operating with said collar, a nut upon the exterior thread of the hollow spindle, pivots projecting from said nut on opposite sides of the same, a horizontal frame carried by said pivots, other pivots extending from said frame at right angles with respect to the first-mentioned pivots, double-armed levers carried by said other pivots, rods extending downwardly from said levers to the shiftable tubular members
- 50 and being indirectly and movably connected with the said nut, bell-crank levers carried by the said branches of the casing and being connected at one arm with one of said rods and at the other arm with one of the said
- 55 members, substantially as set forth.
- 70
- 75

In testimony whereof, I have signed my name to this specification.

WALTHER FRÖB.
